UNITED STATES PATENT OFFICE.

WILHELM WEBER, OF HAYINGEN, GERMANY.

BLASTING-CARTRIDGE.

1,157,270.

Specification of Letters Patent.

Patented Oct. 19, 1915.

Application filed July 8, 1915. Serial No. 38,692.

To all whom it may concern:

Be it known that I, WILHELM WEBER, a subject of the German Emperor, residing at Hayingen, Lorraine, Germany, have invented new and useful Improvements in Blasting-Cartridges, of which the following is a specification.

This invention relates to blasting cartridges consisting of combustible metallic powder, an absorptive substance for liquid air, and a primer.

Blasting cartridges ignitable by means of primers and consisting of a combustible metallic powder and an absorbtive for liquid air are known. However, in such blasting cartridges the absorbtive consists of an inert substance, and the combustible metallic powder is provided in comparatively large quantities in consequence of which the absorbtive for liquid air is diminished. Moreover, in the known blasting cartridges the combustible metallic powder is mixed with the absorbtive, whereby the metallic powder produces a rapid evaporation of the liquid air; thus the explosive power of the cartridge is of very limited duration. Besides, such cartridges as regards their manipulation and explosive effect have not fulfilled the expectations attached to them.

The object of the present invention is to provide a blasting cartridge which is ignitable by a primer and consists also of combustible metallic powder and an absorbtive for liquid air. However, in the new cartridge the absorbtive is not an inert substance but an organic matter of high absorbtive power for liquid air and the combustible metallic powder is separated from the absorbtive and is provided in comparatively small quantities amounting to about $\frac{1}{10}$ or less of the entire contents of the cartridge, for instance, 50 grams for a cartridge of a capacity of one cubic decimeter.

In the accompanying drawings an embodiment of a blasting cartridge according to this invention is shown, Figure 1 representing a sectional elevation and Fig. 2 a cross sectional plan view.

This novel explosive cartridge consists of an outer case *a* preferably double walled with an intermediate layer *e* of corrugated paper, the intervals of which may receive liquid air; of a perforated tube *b* of a comparatively large diameter serving simultaneously as a storage vessel for the liquid air; a detachable cap *f* at the lower end that en-

ables the cartridge to be filled with a non-inert absorptive body *d*, and the bag *c* containing a small proportion of aluminium powder. On the exterior of the cartridge small channels *h* for the reception of the priming wires *p* are provided which may be covered by sheet of paper *i* to prevent injuring the wires while the cartridge is being inserted into the blasting hole.

The absorbtive is first inserted into the cartridge whereafter the bag *c* containing the combustible metallic powder and the primer is added. The bag *c* may be provided with a prolongation *e* filled with cotton or the like to prevent a rapid evaporation of the liquid air in contact with the aluminium powder.

As suitable substances of high absorbtive power being capable to receive a comparatively large quantity of liquid air and to keep same during a longer period of time, substances may be chosen which are combustible, porous, light in weight, and non-conductive for heat like cotton, saw dust, cork, linen and the like. These substances are capable to absorb liquid air to an amount equal to a multiple of their weight and will keep a relevant portion of this quantity for 15 to 20 minutes time which fact may be ascertained by weighing. The high absorbtive power of these substances is of great importance since when these substances are employed there remains a margin of liquid air over the quantity of oxygen required for the combustion which margin through evaporation produces dynamic actions besides other phenomena.

By placing the metallic powder in a bag or smaller cartridge which also contains the primer, a separation of the metal from the absorbtive is obtained. This separation of the metallic powder from the absorbtive which is a special feature of this invention is a requisite because the metallic powder in mixture with the organic substance would not produce the desired effect. Instead of the metallic powder a mixture of several combustible metallic substances may be used, and the organic matter may be substituted by charcoal which is a heat product of organic substances. Through using but small quantities of metallic powder it is made possible to produce a cheap explosive such as is of special value in mining work.

The cartridge is saturated in a most simple manner by pouring the liquid air contained

in a transportable vessel, into the tube projecting from the cartridge; or by dipping the cartridge into liquid air. The absorptive body is saturated with liquid air through the perforated tube from below upward; the complete saturation may be ascertained by touching the intensely refrigerating cartridge with the hand. The cartridge being saturated and the perforated stopper *g* inserted into the end of the tube *b*, the cartridge is placed into the blasting hole which preferably has been filled previously with cold vapors by pouring in some liquid air. In upward inclined blast holes the stopper end of the cartridge is inserted first while in downward inclined blast holes the stopper end is put in last. Finally, the tamping is put in place wherefor but a few seconds time is required. With an explosive charge of a high explosive power such as described in this application, the tamping need only be small. Small holes may be made in the tamping by means of a skewer to provide for the escape of the vapors. The setting of the shots is carried out from a safe position through electrical ignition, or by means of a fuse connected to the primer.

Owing to the particular nature of the absorbent and owing to the arrangement of the metallic powder separate from the absorbent, the degree of saturation is maintained for some time after the blast hole has been tamped. On the other hand, a partial premature evaporation of the nitrogen enriches the liquid air in oxygen, thus the cartridge may be shot some minutes after the miners have gone to a safe place, a high explosion effect will nevertheless be obtained.

In some cases where the blasting hole is provided with a chamber like enlargement the explosive may be applied without a special cartridge but the parts placed separately, by pouring in the liquid air through a tube consisting of a substance non-conductive for heat; even the tamping may with good results be dispensed with then.

This novel blasting cartridge produces a triple effect: 1. A chemical effect caused by the sudden combustion of the metallic powder in liquid air enriched in oxygen, which combustion results from the electrical ignition. 2. A further chemical effect caused by the sudden oxidation of the absorbent soaked with liquid air. 3. A dynamical effect caused by the sudden evaporation of the excess of liquid air. The excess of air rich in oxygen prevents the formation of carbonic acid gas during the oxidation of the absorbent.

Tests carried out with the novel explosive in cylinders of lead measuring 200 millimeters in diameter and 250 millimeters in length and having an inner channel for the reception of the explosive charge, disclosed

surprising results. While blasting cartridges with liquid air of known composition produce a bulging of the leaden cylinder measuring but 2000 cubic centimeters, and with application of dynamite a bulging of 10000 cubic centimeters, the action of the novel explosive is so powerful as to produce a complete bursting of the leaden cylinder. A portion of the cylinder was thrown off, and the air pressure produced by the explosion in a gangway of 2.80 meters in width and 3.75 meters in height was so immense that the heavy iron entrance door at a distance of 50 meters was suddenly opened and the upper iron portion of same thrown away.

Tests carried out in an iron ore deposit produced not less favorable results. In opening a new gallery in an ore deposit, with a single shot 21 tons of ore could be got in. In another gallery, an opening shot was set in a depth of 1.2 meters; the result produced by the novel blasting cartridge was such that a mass of ore was thrown off that measured 1 meter in depth, 2 meters in width, and 2.1 meters in height. In both cases cartridges had been employed having a capacity of 1000 cubic centimeters and containing but 50 grams of aluminium powder filled in bags and placed separately from the saw dust used as absorbent for the liquid air. The employment of but small quantities of aluminium powder reduces the costs of the cartridge considerably in comparison with other explosives producing an identical effect.

To ascertain the degree of safety in manipulating the novel blasting cartridge the following tests have been carried out: 1. The flame of an acetylene lamp could be extinguished by pouring liquid air upon the flame. 2. An ignited match extinguished in contact with liquid air. 3. A finished saturated cartridge was held for 10 minutes in contact with the flame of an acetylene lamp; no explosion occurred. 4. A weight of 20 kilograms was allowed to drop from a height of 1.5 meters upon the cartridge placed vertically but having its lower part containing the primer protected; no explosion of the cartridge occurred.

Having thus described my invention, what I claim is:—

1. A blasting cartridge, consisting of an outer casing, an organic non-inert absorbent for liquid air within said casing, a perforated storage tube for liquid air surrounded by said absorbent, a separate package of metallic powder inside said casing, and a primer in contact with said metallic powder, substantially as and for the purpose described.

2. A blasting cartridge, consisting of a double walled outer casing, a corrugated layer of paper intermediate of the walls of

said outer casing, an organic non-inert absorbent for liquid air, a perforated storage tube for liquid air inside said casing and surrounded by said absorbent, a separate package of metallic powder inside said casing, and a primer in contact with said metallic powder, substantially as and for the purpose described.

3. A blasting cartridge, consisting of a double walled outer casing, a corrugated layer of paper intermediate of the walls of said outer casing, an organic non-inert absorbent for liquid air within said casing, a perforated storage tube for liquid air surrounded by said absorbent and projecting from said outer casing, a perforated stopper for the outer end of said perforated tube, a separate package of metallic powder inside said casing, and a primer in contact with said metallic powder, substantially as and for the purpose described.

4. A blasting cartridge, consisting of a double walled outer casing, a corrugated layer of paper intermediate of the walls of said outer casing, channels on the exterior of said outer casing adapted to receive priming wires, an organic non-inert absorbent for liquid air, a perforated storage tube for liquid air surrounded by said absorbent and projecting from said outer casing, a perforated stopper for the outer end of said perforated tube, a separate package of metallic powder inside said casing, a primer inside said package in contact with said metallic powder, and a pair of priming wires embedded in said channels and connected to said primer, substantially as and for the purpose described.

5. A blasting cartridge, consisting of an outer casing, an organic non-inert absorbent

for liquid air, a perforated storage tube for liquid air inside said casing and surrounded by said absorbent, a separate package containing metallic powder to the amount of about $\frac{1}{6}$ of the capacity of the cartridge, 45 and a primer in contact with said metallic powder, substantially as and for the purpose described.

6. A blasting cartridge, consisting of an outer casing, an organic non-inert absorbent 50 for liquid air, a perforated storage tube for liquid air inside said casing and surrounded by said absorbent, a separate package of metallic powder inside said casing and a cotton filled extension of said package interposed 55 between said storage tube for liquid air and said metallic powder, and a primer in contact with said metallic powder.

7. A blasting cartridge, consisting of a double walled outer casing, a corrugated 60 layer of paper intermediate of the walls of said outer casing, channels arranged lengthwise on the exterior of said outer casing and adapted to receive priming wires, a paper cover over said channels, a perforated storage tube for liquid air inside said casing and surrounded by said absorbent which storage tube projects from said outer casing, a perforated stopper for the outer end of said perforated inner storage tube, a 70 closed bag inside said outer casing containing metallic powder and a primer inside said metallic powder, and a cotton filled prolongation of said bag separating said metallic powder and said liquid air, and 75 priming wires embedded in said channels and connected to said primer substantially as and for the purpose as described.

WILHELM WEBER.
